PROCESS FOR PRODUCING GASES

Augustus B. Kinzel, Flushing, N. Y., assignor,
by mesne assignments, to Union Carbide and
Carbon Corporation, a corporation of New
York

Application June 22, 1933, Serial No. 677,074

2 Claims. (CL 23—5)

The invention relates to the production of gases for use as an atmosphere in which to heat treat metals and alloys, and has for its chief object the provision of a new and useful process for producing gases for bright annealing.

Heat treatment of metals and alloys is usually done in the presence of air, with the result that the surface of the metal is discolored or even attacked sufficiently to form a scale which must be removed by pickling, grinding, or sand-blasting. A desire to eliminate the damage to metal surfaces during heat treatment, especially during annealing, has led to the use of reducing or relatively inert atmospheres during the treatment. Thus, illuminating gas, natural gas fractions, carbon monoxide, cracked ammonia, pure hydrogen, and pure nitrogen, have each been proposed for the purpose. However, all of these gases have one or more of the disadvantages of being toxic, explosive, flammable, expensive, or ineffective to prevent the surface discoloration of all metals and alloys.

Research indicates that in order to anneal or otherwise to heat treat metals and alloys at elevated temperatures without substantial attack or discoloration of the surface of the metal, it is necessary to use an atmosphere which is substantially free from oxygen, oxygen-containing gases such as water vapor and oxides of carbon, and from gases which tend to deposit carbon on the metal, for instance, saturated and unsaturated hydrocarbons. For obvious reasons, the atmosphere preferably is non-toxic and non-explosive when mixed with air in any proportions.

Mixtures of nitrogen and hydrogen containing up to about 7% hydrogen, nonflammable in air, and mixtures of nitrogen and hydrogen containing up to about 15% hydrogen, non-explosive in air, each substantially free from oxygen, oxygen-containing gases, and gases which tend to deposit carbon on the work, are admirably suited for bright annealing and other high temperature treatments of metals and alloys.

It is an object of the invention to provide a practicable process for producing substantially pure mixtures of hydrogen and nitrogen for bright annealing.

A further object of the invention is to provide a practicable, efficient, and relatively inexpensive process for producing for bright annealing substantially pure mixtures of hydrogen and nitrogen, using hydrocarbons, preferably natural gas fractions, as the raw material.

These and further objects of the invention are attained in the process which will be described

herein below, with reference to the drawing, in which

The single figure is a diagrammatic flow sheet of the process.

The process in the preferred form shown in 5 the drawing comprises thermally cracking a portion of gaseous or vaporized hydrocarbons completely to carbon and hydrogen, separating the hydrogen from the carbon, cooling and cleaning the hydrogen and storing it temporarily in a 10 holder; burning another portion of hydrocarbons with air to produce a mixture containing nitrogen, carbon dioxide, and water, and cooling the combustion products; passing a portion of hydrogen from the holder in heat exchange relationship to, but out of direct contact with, a portion of the cooled combustion products, whereby the hydrogen and combustion products are brought to substantially the same temperature; 15 thoroughly mixing in predetermined proportions 20 hydrogen and combustion products at substantially the same temperature; scrubbing the mixture to remove substantially all of the carbon dioxide, refrigerating the mixture to remove most of the water; desiccating the mixture to remove 25 substantially all traces of moisture; and subjecting the mixture to a final purification treatment with a suitable active material to remove substantially all traces of oxygen-containing 30 gases.

While it will usually be desired to add the hydrogen to the combustion products before the carbon dioxide scrubber, under some conditions it may be desired to mix the hydrogen with the nitrogen after the latter has been scrubbed or even after the nitrogen has been dried or purified.

Although any efficient hydrocarbon cracking device which will produce hydrogen substantially free from hydrocarbons and oxygen may be used 40 in the process of the invention, I prefer to use the cracking furnace and its auxiliary apparatus disclosed and described in the copending application of G. D. Bagley and H. Erasmus, filed June 22, 1933, Serial Number 677,024. The apparatus therein described may be used to produce relatively pure hydrogen from hydrocarbons, and to utilize the heat of combustion of the carbon so obtained to supply the heat required for crack- 45 ing.

Further, while I may employ any effective method and apparatus for converting a mixture of hydrocarbon fuel gases and air into a mixture of nitrogen, carbon dioxide, water vapor and hydrogen substantially free from hydrocarbons, 50

carbon monoxide and oxygen, I prefer to use the method and apparatus described in the copending application of John J. Egan, filed June 22, 1933, Serial Number 677,047, wherein a mixture of hydrocarbons and air in predetermined proportions are ignited, and the combustion products are passed over an oxidation catalyst to complete the oxidation of the carbon.

For the final purification step, the gas may be passed over or through any actively oxidizable material, for example, alkali metals, alkaline earth metals, or non-volatile active organic reducing agents; but I prefer to use a molten partial eutectoid mixture of metallic sodium and potassium mixture, as described in the copending application of Hendrik Eraäsmus, filed November 17, 1933, Serial Number 698,550.

The scrubbing device for removing carbon dioxide may be a packed tower, or a tower provided with trays or trays and bubble-caps, and the scrubbing liquid may be a solution of a carbonate, an amine or other suitable alkaline or basic liquid. If desired, the scrubbing may be done under pressure, in known manner. A scrubbing liquid which may be regenerated by stripping out the carbon dioxide, and recirculated through the scrubber, is to be preferred.

The refrigerator may consist of cooling pipes containing cold brine, over the outer surface of which pipes the gas is passed; or the gas may be passed in counter-current flow to, and in direct contact with, a stream of cold brine.

The desiccator may consist of a tower packed with a solid which will absorb or react with moisture, for example, calcium carbide, calcium oxide, or sodium hydroxide.

Auxiliary apparatus such as gas mixers, coolers, and heat exchangers, may be standard types and designs.

While the above described process steps are preferred, modifications thereof are possible. Almost any vaporizable and combustible fuel, for instance, illuminating gas, natural gas, natural gas fractions, producer gas, or petroleum fractions, may be used as fuel in the production of nitrogen and carbon dioxide; or a part of the hydrogen obtained from the cracking stage may be used as the fuel. If hydrocarbons are used in the combustion stage, an excess of hydrocarbons may be used so as to produce thereby a part of the hydrogen desired in the final annealing gas. In some circumstances it will be possible and desired to use a refrigerated scrubbing liquid in the CO₂ scrubber, rather than to use a separate refrigerating device; or to eliminate the desiccating step or the final purification step, or both. However, although each of these variations may be suitable under certain circumstances and conditions, they do not provide as satisfactorily flexible or efficient a process as the preferred form for producing mixtures of great

purity and controllable hydrogen content under all conditions.

I claim:

1. Continuous process for producing bright annealing gases which comprises the steps of mixing thoroughly a hydrocarbon fuel with air; burning the said mixture in the presence of an oxidation catalyst to produce a nitrogen-containing gas free from more than traces of carbon monoxide, oxygen, and hydrocarbons; intermittently thermally cracking hydrocarbons in the absence of air, steam, or other oxygen-containing gas, to produce hydrogen free from more than traces of oxygen, and hydrocarbons; temporarily accumulating the hydrogen so produced to provide a source from which hydrogen can be withdrawn continuously; passing a stream of said hydrogen in heat exchange relationship to, but not in direct contact with, a stream of said nitrogen-containing gas, whereby the two streams are brought to substantially the same temperature; thoroughly mixing in predetermined proportions the said hydrogen and nitrogen-containing gases to form a mixture in which the hydrogen is not more than about 15% of the mixture; scrubbing the last-mentioned mixture with a basic solution whereby to remove substantially all carbon dioxide; refrigerating the scrubbed mixture to remove the major part of the water; and finally desiccating the gas.

2. Continuous process for producing bright annealing gases, which comprises withdrawing a supply of hydrocarbon gas from a suitable source or sources thereof; dividing the supply of hydrocarbon gas into two portions; thoroughly mixing one portion of the hydrocarbon gas with air; burning the said mixture in the presence of an oxidation catalyst to produce a nitrogen-containing gas free from more than traces of carbon monoxide, oxygen, and hydrocarbons; intermittently thermally decomposing the other hydrocarbon portion in a self-sustaining cyclical process whereby to produce hydrogen free from more than traces of oxygen and hydrocarbons; temporarily accumulating the hydrogen so produced to provide a source from which hydrogen can be withdrawn continuously; passing a stream of said hydrogen in heat exchange relationship to, but not in direct contact with, a stream of said nitrogen-containing gas, whereby the two streams are brought to substantially the same temperature; thoroughly mixing in predetermined proportions the said hydrogen and nitrogen-containing gases to form a mixture in which the hydrogen is not more than about 15% of the mixture; and purifying the last-mentioned mixture to remove substantially all carbon dioxide and water.

AUGUSTUS B. KINZEL.
